Merle G. Carr
ATTORNEY

UNITED STATES PATENT OFFICE

JAMES C. WOODSON, OF MANSFIELD, OHIO, ASSIGNOR TO WESTINGHOUSE ELECTRIC & MANUFACTURING COMPANY, A CORPORATION OF PENNSYLVANIA

ELECTRIC HEATER

Application filed April 11, 1929. Serial No. 354,280.

My invention relates to electrically heated devices and more particularly to tubular heating units.

An object of my invention is to provide a compact, simple and highly efficient heater for heating tubular members of varying lengths.

Another object of my invention is to provide a tubular electric heater that shall embody means for cooling that portion of the heater that is not located within a hollow object being heated.

Another object of my invention is to provide a portable tubular heater that shall embody means for carrying the same and also means for limiting the movement of a cooling means, adjustably located thereon, in one direction.

In practicing my invention, I provide an elongated tubular heater comprising an outer metallic sheath, a helically-wound resistor member insulatedly located within the sheath, a terminal box secured to one end of the heater, a control switch and a carrying means supported by the terminal box, and a cooling means that may be adjustably clamped on, and cover a portion of, the surface of the tubular heater.

In the single sheet of drawing, Figure 1 is a view, in longitudinal section through a portion of the heater, taken on the line 1—1 of Fig. 2,

Figure 2 is a plan view, of one end of a tubular heater embodying my invention, and

Fig. 3 is a view, partially in plan and partially in section, of the other end of such a heater.

In the construction and assembly of relatively large fluid-turbine casings, it is highly desirable that the flange portions of co-acting sections of the casings be held tightly clamped relatively to each other in order that no leakage of the motive fluid may occur. Tubular bolts are used and it is desired to heat these bolts, either just before they are located in their proper operative positions in the aligned openings in the flanges of adjacent turbine sections or while they are in their proper operative positions, in order that the nuts thereon may be drawn up as tightly as

possible while the bolts are hot, after which the bolts are permitted to cool, whereby a greater clamping action may be obtained than would otherwise be the case.

A portable heater for heating tubular bolts embodies a substantially tubular heating unit 12 having an outer metal casing 13 and an enclosed helically-wound resistor 14, which is embedded in suitable electric-insulating material 16. The tubular member 12 may be of any suitable or desired length, corresponding to the maximum length of a tubular bolt 17 which it is desired to heat. The helically-wound resistor 14 extends through a portion only of the length of the outer metallic casing 13, as is shown more particularly in Fig. 2 of the drawing. Terminal leads 18 and 19 extend through the other portion of the casing 13 and into a terminal box 21 which is so designed and constructed that it may be mounted on, and supported by, one end of the metallic casing 13 and be held thereon by a set screw 22.

The terminal box 21 includes a cylindrical portion 23 within which is located a suitable control switch 24, here shown as of the snap-switch type. The depth of the cylindrical member 23 is made large enough so that the handle 26 of the snap switch is protected thereby.

A twin conductor cord 27 may be of any suitable or desired length and of such current-carrying capacity as may be required by the amount of energy which is translated into heat in the resistor 14. The inner end of the cord 27 extends into the terminal box 21 through a bushing 28 of any suitable electric-insulating material and may be provided with a knot 29 in order to prevent the cord slipping or pulling out from the terminal box and thus exerting a strain upon the connections between the cord, the terminal members of the switch 24 and the ends of the terminal leads 18 and 19.

A carrying means 31 of substantially U-shape is provided for the heater and may have end portions of the legs thereof suitably secured against lugs 32 provided on the outside of the terminal box 21.

I have shown a hollow bolt 17 as being lo-

- cated in aligned openings in two adjacent flanges 33 and 34, which flanges are intended to represent the flanges of adjacent sections of a large turbine casing. A nut 36 is located 5 on the other end of the body of the bolt 17 and is to be tightened as much as possible thereon after bolt 17 has been heated in order to tightly clamp the flanges 33 and 34 together when the bolt cools.
- 10 As was hereinbefore stated, a heater of this type may be called upon to heat tubular objects of different lengths and, in order to provide means for cooling that part of the tubular heating unit which is not located within 15 the tubular object, I provide a two-part clamp-on cooling means embodying two elongated similar metal portions 37 and 38. These two metal portions are located in opposed facing relation and are held in tightly 20 clamped location in a predetermined position on the tubular member 12 by means of pairs of clamping bolts 39 and 41, each pair being located adjacent to one end of the members 37 and 38, nuts 42 and 43 being provided 25 thereon in the usual manner. When the two parts 37 and 38 are located in opposed relation, an opening is provided therebetween of substantially circular shape in lateral section and of such dimension as to permit of the 30 tight clamping relation. A plurality of laterally extending fins 44 are provided on each of the portions 37 and 38 in order to increase the heat-radiating or cooling surfaces of 35 these members, the number and spacing of such fins being such as to obtain the desired result; namely, to maintain the temperature of that part of the heating unit not located within the tubular object at a relatively low value which will not injure the resistor and the 40 insulation.
- Means for limiting the movement of the clamp-on cooling means in one direction longitudinally of the unit 12 embodies a pair of chains 46 and 47 one end of each of which 45 is secured to the end of the corresponding leg portion of the carrying means 31, while the other ends of these chains are secured to the rear ends of the members 37 and 38, as by screws 48.
- 50 While I have shown the tubular heating unit embodying my invention as located in operative relation to a hollow bolt, it is, of course, obvious that its use is not restricted thereto and that it may be used for the heating 55 of any hollow objects or appliance.
- The device embodying my invention thus provides a relatively simple, lightweight, portable, tubular heating unit adapted to be operatively related to, and have any predetermined portion of its length inserted within, a hollow object to be heated, that portion of the heating unit which is not enclosed by the hollow object being provided 60 with an adjustable clamp-on cooling means 65 to ensure that the temperature of the unused

portion of the heater shall also be below a value which might prove dangerous to the resistor.

Various modifications may be made in the device embodying my invention without departing from the spirit and scope thereof, and I desire, therefore, that only such limitations shall be placed thereon as are imposed by the prior art or are set forth in the appended claims.

I claim as my invention:

1. A portable electric heater including a straight tubular heating unit, a terminal box secured to one end of the tubular heating unit, a control switch for the heating unit in said terminal box, carrying means secured to the terminal box, cooling means for a part of the heating unit adjustably securable thereon and means operatively connecting the carrying means and the cooling means for limiting the adjustable movement of the cooling means in one direction.

2. A portable electric heater including a straight tubular metal-clad heating unit, a portion of whose lengths is to be inserted in a hollow object to be heated, and a two-part clamp-on metal cooling means located on that part of the tubular heating unit located outside of the object being heated to prevent excessive temperature rise of that part of the heating unit located outside of the object being heated.

3. An electric heater including an elongated tubular heating unit and a cooling means for a portion of the heating unit including a two-part structure to surround a predetermined portion of the length of the unit less than its total length and means for adjustably clamping the cooling means on the heating unit.

In testimony whereof, I have hereunto subscribed my name this 3rd day of April, 1929.

JAMES C. WOODSON.
